UNITED STATES PATENT OFFICE.

ARTHUR E. KRICK, OF DANVILLE, INDIANA, ASSIGNOR TO THE HUMIDITY CONTROL COMPANY, OF INDIANAPOLIS, INDIANA, A CORPORATION OF INDIANA.

HUMIDITY REGULATOR.

Application filed October 22, 1923. Serial No. 669,910.

It is the object of my invention to improve and accelerate kiln-drying, with especial reference to the drying of lumber.

More specifically, it is the object of this present invention to improve and develop the control apparatus shown in my co-pending application Serial No. 551,053, filed April 10, 1922, for carrying out in a preferred way the process of kiln-drying set forth in my co-pending application Serial No. 671,111, filed October 27, 1923; which process contemplates kiln-drying, and particularly the kiln-drying of lumber, by alternately decreasing and increasing the relative humidity of the drying air between wide limits.

It is a further object to produce a control apparatus, especially for use in the control of kiln-drying, which will have a snap action on the control member, as on a valve or valve-stem, will act to hold such control member in either position substantially until it is desired to move it to the other position, and will do so by floating spring-actuated members which act on the control member without exerting side-pressure thereon.

The accompanying drawings illustrate my invention: Fig. 1 is a transverse section through a dry-kiln equipped with my control apparatus; Fig. 2 is a side elevation of my control apparatus, with some parts broken away or in section, showing actuation by wet-bulb control only; Fig. 3 and Fig. 4 are fragmental views similar to the middle portion of Fig. 2 but showing the movable parts in intermediate positions in the upward and downward movement respectively of the actuating member; Fig. 5 is a transverse section substantially on the line 5—5 of Fig. 4; Fig. 6 is an elevation of the device on a smaller scale than Fig. 2, so that the complete device may be shown; Fig. 7 is a view similar to Fig. 2, on a somewhat smaller scale, showing actuation by joint wet-bulb and dry-bulb control, as is also illustrated in Fig. 1; and Fig. 8 is an elevation, in partial section, of my control apparatus arranged to exert its controlling action through a pilot valve.

The dry kiln 10 in which the conditions are controlled may be of any desired type, with any suitable heating means 11 and with any suitable air-humidifying means 12, and with any suitable arrangements for supporting the lumber or other material to be

dried, such as the tracks 13 for supporting trucks which carry such lumber. As shown, both the heating means 11 and the air-humidifying means 12 are steam coils. They are shown below the tracks 13, but this is immaterial; and the air-humidifying coils are shown as being in part coils located in water in a water-tank 14, to produce evaporation of water from such tank, and in part as steam-spray coils, though either type of air-humidifying coils may be used alone, or other types of air-humidifying means may be used instead. The steam for both heating and humidification is shown as being supplied from a main steam-supply line 15, which is branched to provide a supply line 16 leading to the heating coils 11 and a supply line 17 leading to the air-humidifying coils 12. The details of the kiln and of the heating and humidifying means thereof are not part of my present invention, and may be anything desired; and are shown to exemplify the application of the controller which is the subject-matter of this present invention.

In the supply line 16 to the heating coils 11 is a control valve 20, which I prefer shall be automatically controlled to maintain a definite dry-bulb temperature within the kiln, usually a uniform temperature at least for a given period. To obtain this, the heat-control valve 20 is operated by a fluid-pressure motor-member 21 connected by a pipe 22 to a suitable vapor-pressure thermostat 23 within the kiln 10. If the temperature rises in the kiln, the vapor-pressure developed in the thermostat 23 also rises to cause the motor-member 21 to move the valve 20 toward closed position, to cut down the supply of heating steam to the heating coils 11; while if the temperature falls the reverse series of actions takes place, to increase the supply of steam to the heating coils 11. The motor-member 21 and valve 20 are conveniently provided with suitable adjusting means, such as an adjustable weight 24, by which the temperature which is maintained in the kiln may be varied from time to time, as the drying proceeds.

In the supply line 17 to the air-humidifying means 12 is a control valve 30. It is to this valve 30 that the control apparatus which forms the subject of this present invention is shown applied in Figs. 1, 2, and 6; and the control of the heat-regulating

valve 20 is merely incidental to this, so far as my present invention is concerned, as the control of the heat merely assists in the control of the relative humidity.

I have shown the valve 30 as a balanced valve, having a twin valve-member 31 movable with relation to twin valve-seats 32 to open and close the valve. In Fig. 2 the valve is shown open in full lines and closed in dotted lines. These positions are the limiting positions, the closing movement being limited by the seating of the valve-member 31, and the opening movement being limited by a stop 29 against which a central boss on the upper valve-disk 31 may abut. The valve-member 31 has a valve-stem 33, which is connected through a lost-motion connection 34 to a shifter rod 35. This lost-motion connection will be discussed more fully later. The shifter rod 35 is controlled in response to variations in relative-humidity within the kiln 10 to open the valve 30 when the relative-humidity drops to a certain low value, say 30%, and to close such valve 30 when the relative humidity rises to a certain high value, say 98%, but to be without effect on the valve for intermediate relative humidity until the limiting relative humidity is approached. In consequence, when the valve 30 is closed, the relative humidity drops gradually until its low value is approached; whereupon the valve 30 is opened to admit air-humidifying steam, to cause the relative humidity to rise until the high value is approached; whereupon the valve 30 is again closed, and the cycle is repeated. The drop in relative humidity is relatively slow, and the rise relatively rapid.

The shifter rod 35 may be operated in response to variations in wet-bulb temperature alone, as indicated in Fig. 2, or in response to variations both in wet-bulb temperature and in dry-bulb temperature, as illustrated in Figs. 1 and 7. The latter form is preferable when there is no automatic control of the dry-bulb temperature of the kiln by the valve 20; but when the dry-bulb temperature of the kiln is automatically controlled by the valve 20 as already explained, so that the variations in dry-bulb temperature within the kiln are relatively slight over a given period, it is ordinarily unnecessary to use the dry-bulb temperature for assisting in the control of the movements of the shifter rod 35, so that in such cases I prefer the simpler arrangement shown in Fig. 2 where the movements of the shifter rod 35 are obtained wholly by variations in wet-bulb temperature.

In either case, the shifter rod 35 is provided with a thrust-plate 36, which is pressed downward by a fluid-pressure expansible motor-member 38 connected by a pipe 40 to a wet-bulb vapor-pressure thermostat 42 located at a desired point in the

kiln 10. The pressure developed by this wet-bulb thermostat 42 thus tends to move the shifter rod 35 downward, to close the valve 30. This wet-bulb thermostat may be kept wetted in any suitable way, as by a wick 43 which overlies such wet-bulb thermostat and dips into water maintained at a constant level in a water-tank 44 by a suitable float-valve 45. If the shifter rod is also jointly controlled by dry-bulb temperature, as indicated in Figs. 1 and 7, a second fluid-pressure expansible motor-member 37 acts upwardly on the thrust-plate 36, in opposition to the motor-member 38; which second motor-member 37 is connected by a pipe 39 to a dry-bulb thermostat 41 also located within the kiln 10.

The shifter rod 35 is connected to a lever 46, suitably mounted on a fixed pivot 47. The lever 46 carries a normally fixed but adjustable weight 48, for adjusting in common the points at which the valve operates; and also carries a shifting weight 49 which is arranged to slide along the lever 46 between two stops 50 and 51, shown as provided with buffer springs to cushion the stopping of the shifting weight 49. To reduce the sliding friction, the weight 49 is preferably carried by rollers 52 which travel on the upper face of the lever 46. The stops 50 and 51 may be adjusted along the lever 46, to control separately the points of high-humidity and low-humidity at which the valve operates; and while in the arrangement shown in Figs. 1, 2, and 6 such adjustment is manual, the stops being provided with set-screws 53 by which they are clamped in adjusted position, my invention is not limited to such manual adjustment, and in my aforesaid co-pending application Serial No. 551,053 I show an arrangement for automatically varying the position of these stops.

The apparatus as so far described does not differ from that set forth in my aforesaid application Serial No. 551,053. The difference which constitutes the basis for this present application resides primarily in the inter-connection between the shifter rod 35 and the valve-stem 33, and in the parts associated therewith for obtaining the desired movements of the valve and valve-stem; and secondarily in the mounting of the lever 46 on the pivot 47, to provide adjustment of the angular position of the lever 46 for a fixed position of the shifter rod 35 and thrust-plate 36 so that the lever 46 may be made to pass through the horizontal to get shifting of the shifting weight 49 at different positions of the thrust-plate 36, and to provide for installations under different conditions.

Referring first to the interconnection between the shifter rod 35 and the valve-stem 33: The valve-stem 33 has two spaced abut-

ments 100 and 101, either or both of which may be adjustable, between which plays a finger 102 carried by the shifter rod 35. The space between the two abutments 100 and 101 is materially greater than the thickness of the finger 102, so that the lost-motion of the connection will be provided thereby. Two toggle-arms 103 and 104 are pivoted in common at their adjacent ends on the valve-stem 33 or on one of the abutments thereon, being shown as pivoted on a pivot-pin 105 on the abutment 100. The outer ends of these toggle-arms 103 and 104 are interconnected by a tension spring 106, which tends to pull the two toggle-arms out of line with each other in either direction in which such toggle-arms at any time may be out of line. The toggle-arm 103 is mounted at an intermediate point on a floating pivot-pin 107, carried by a swinging arm 108. Preferably the floating pivot-pin 107 is mounted on a supporting plate 109 which is adjustable by screw-and-slot connections 110 along the arm 108, to vary the point in the movement of the toggle-arm 104 at which the latter comes into line with the toggle-arm 103. The toggle-arm 104 is connected by a link 111 to one end of a lever 112, the other end of which lever is connected to the shifter rod 35 or to the finger 102—to the finger 102 as shown—by a pivot-pin 113. The lever 112 is pivoted at an intermediate point to the lower end of a swinging arm 114, the upper end of which is pivotally hung from a suitable support 115 on the frame of the controller.

In operation, assume that the parts are as shown in full lines in Fig. 2, with the valve 30 open, so that humidifying steam is being supplied to the dry-kiln. As such steam is supplied, the relative humidity of the air in the kiln is raised, which causes the wet-bulb temperature of such air to rise. This rise causes the production of a greater pressure in the wet-bulb thermostat 42, which pressure is communicated to the motor-member 38 to cause it to exert a greater downward thrust on the thrust-plate 36. This causes the shifter rod 35 to move downward as the relative humidity in the kiln rises. This action occurs whether or not the motor-member 38 is opposed by another motor-member 37. As the thrust plate 36 and shifter rod 35 are thus pushed downward, the right-hand end of the lever 46 is gradually swung downward, to cause the lever 46 to pass through the horizontal position to a position in which it slants the other way. Shortly after the lever 46 has passed through the horizontal, the shifting weight 49 is moved by gravity inward along such lever 46, or from the stop 50 to the stop 51. Such movement lessens the mechanical advantage of such shifting weight, and thus relatively increases the mechanical advan-

tage of the counterweight 48 and of the motor-member 38 on the lever 46, so that they may act to move such lever 46 more rapidly than at first. In addition to these things, the downward movement of the shifter rod 35 upon the increase in relative humidity moves the finger 102 away from the abutment 101 toward the abutment 100 on the valve-stem 33, to take up the lost-motion of the connection. As the finger 102 moves downward, it carries the pivot-pin 113 with it, to swing upward the right-hand end of the lever 112 and the right-hand end of the toggle-arm 104, to move the parts from the position shown in full lines in Fig. 2 through the position shown in Fig. 3 to the position shown in dotted lines in Fig. 2. In Fig. 3 the parts are shown with the lost-motion above referred to taken up, and the finger 102 against the abutment 100. As the downward movement of the shifter rod 35 continues beyond the position shown in Fig. 3, the continued upward movement of the right-hand end of the lever 112 is now accompanied by a pushing downward of the pivot-pin 105 to accelerate such upward movement of the right-hand end of the toggle-arm 104 and to cause an upward movement of the left-hand end of the toggle-arm 103. This soon brings the two toggle-arms into line, and then out of line again in the other direction; whereupon the spring 106 acts to swing the outer ends of the two toggle-arms 103 and 104 farther upward, to depress the pivot-pin 105 and the valve-stem 33 and thus to assist in seating the valve disks 31 on their seats 32. The parts are preferably adjusted so that the shifting of the weight 49 and the passing of the toggle-arms 103 and 104 through alinement occur at about the same time; though exact simultaneity in these two actions is not necessary. Until the downward movement of the shifter rod 35 has passed beyond the point shown in Fig. 3, the spring 106 in its action on the toggle-arms 103 and 104 serves to hold the valve 30 wide-open, and prevents it from jarring closed or from being carried toward or to closed position by the action of the steam; but shortly after the position shown in Fig. 3 has been passed the combined effects of the spring 106 and the shifting of the weight 49 act to cause the closing of the valve, and the spring 106 then serves to hold the valve firmly seated.

The closing of the valve 30 shuts off the supply of humidifying steam to the kiln. In consequence, for a considerable period thereafter, the relative humidity in the kiln slowly decreases; whereas the rise in relative humidity just described was relatively rapid. As such relative humidity thus decreases, the pressure developed in the wet-bulb thermostat 42 also decreases, so that the motor-member 38 exerts less downward pressure

on the thrust-plate 36. In consequence, such thrust-plate is gradually moved upward, under the influence of the weight 49, and of the motor-member 37 if that is provided. 5 This upward movement carries the parts from the position shown in dotted lines in Fig. 2 through the position shown in Fig. 4 to the position shown in full lines in Fig. 2. As the thrust-plate 36 rises, the finger 102 leaves the abutment 100 and approaches 10 and then engages the abutment 101. This upward movement of the finger 102 moves the right-hand end of the toggle-arm 104 downward, to the position shown in Fig. 4, 15 which shows the parts with the finger 102 engaging the abutment 101. During this time the spring 106 has continuously held the valve disks 31 on their seats 32. As the upward movement of the shifter rod 35 and 20 finger 102 now continues, both outer ends of the toggle-arms 103 and 104 move downward, into and past alined position, whereupon the spring 106 begins to operate in the other direction on the valve-stem 33, and 25 tends to open such valve; which opening of the valve it assists in. In the meantime the left-hand end of the lever 46 has been swinging downward, to and through horizontal position; and the shifting weight 49 rolls 30 downward and outward on the lever 46, at about the time the spring 106 begins to act upwardly on the valve-stem 33. This shifting increases the mechanical advantage of 35 such weight, so that thereupon the opening of the valve proceeds relatively quickly, to admit steam for humidifying the dry-kiln.

The cycle above described is repeated as occasion requires, throughout the drying period of the kiln.

40 In the actions described, the valve-stem 33 is acted on only longitudinally. The various links and levers, with the spring 106, are so designed that they exert no transverse force on such valve-stem, and thus they 45 leave the valve-stem free for its longitudinal movement when the time for that arrives. In other words, the toggle 103—104—106 is a floating toggle; and the lever 112 is a floating lever, because of the swinging supports provided by the arms 108 and 114 and the link 111. This makes for free operation, and for accuracy in operation.

50 In order to adjust the point in the movement where the shifting of the weight 49 occurs, I preferably provide the adjusting mechanism shown in the upper part of Fig. 2. I do not pivot the lever 46 directly on the pivot-pin 47, but on such pivot-pin I mount a fulcrum sleeve 120, which loosely 55 receives the lever 46. The lever 46 has a pivotal connection 121 to the fulcrum sleeve 120 near one end of the latter, and may be angularly adjusted on such pivotal connection by opposed adjusting screws 122 provided in such sleeve near the other end

thereof and acting on the upper and lower edges of the lever 46. By different settings of the screws 122, it is possible to set the lever 46 in a horizontal position for any point throughout quite a range of the movement of the thrust-plate 36. 70

Further, by providing the sleeve 120 separate from the lever 46, it becomes possible to reverse their relative positions if that is desired in mounting the instrument. Not 75 only can the relative positions of the sleeve 120 and the lever 46 be reversed, but the sleeve 120 may be reversed in its mounting on the upper end of the frame 123 of the controller; for the pivot-pin 47 may be received in either of two sets of supporting ears 124 on such upper end. Such two sets of supporting ears are on opposite sides of the shifter rod 35, as is clear from Fig. 2. This double reversibility is of considerable 80 advantage in making installations in crowded places, because with the controller upright it permits assembly in four different relationships of the parts, as may be most convenient in the particular location; and 85 is also of assistance in installing in case it is desired to invert the whole controller, as may be done. The controller works either upright or inverted, and in either case it works with the pivot-pin 47 in either set of 90 ears 124, and with the shifting weight 49 on either side of the sleeve 120; which makes eight possible positions of installation. Indeed, so long as the lever 46 is arranged to 95 swing in a substantially vertical plane, it is impossible to assemble the parts in any of these eight possible positions without obtaining an operable assembly which acts as 100 above described. For none of these eight positions is it necessary that the plane of 105 movement of the lever 46, the plane of movement of the toggle 103—104—106, and the directions in which the fluid-supply and 110 fluid-discharge pipes extend from the control valve, bear any specific relation to each other, and the relations of these things among themselves may be varied as desired to suit the conditions encountered.

Further, the control valve which the controlling apparatus operates need not be the 115 main control valve, although it is so shown in the figures above described. Instead, the main humidity control valve may be controlled by any suitable interposed pilot mechanism, which in turn is operated by the 120 controlling apparatus.

One such arrangement is shown in Fig. 8. There the controlling apparatus directly operates a pilot valve 130, which by its movements controls a supply of power to 125 a suitable power-operated mechanism for the main valve 30. This arrangement may take various forms, and only one example is shown.

The controlling apparatus proper is that 130

already described, and may be governed in either way already described, either by wet-bulb variations alone or by wet-bulb and dry-bulb variations jointly. The valve-stem 5 33 of the control valve—in this case it is the stem of the pilot valve 130—moves up and down in the manner already described upon variations in the governing conditions. The pilot valve 130 controls the connections of a 10 fluid-pressure-supply pipe 131 and of a waste pipe 132 to two pipes 133 and 134 which lead to the two ends of a cylinder 135 in which there is a piston 136 attached to the stem 137 of the main valve 30 to be controlled. When the valve 30 is open and the 15 relative humidity rises, as previously described, the valve-stem 33 is eventually moved downward from the upper position in which it is shown to its lower position; in 20 which latter position it connects the pressure-supply pipe 131 to the pipe 133 leading to the upper end of the cylinder 135 and connects the pipe 134 from the lower end of such cylinder to the waste pipe 132, so 25 that the fluid-pressure will force the piston 136 downward from the position shown to close the main valve 30 and thus cut off the supply of humidifying steam. As the relative humidity now falls, as previously 30 described, the valve stem 33 is eventually moved to its upper position; in which position it reverses the connections from the pipes 131 and 132 to the pipes 133 and 134 from those just described, to make the 35 connections the drawing shows and admits pressure to the lower end of the cylinder 135 while allowing the fluid to waste from the upper end of such cylinder, so that the piston 136 will move upward to open the main 40 valve 30 to admit humidifying steam to cause the relative humidity again to increase.

I claim as my invention:

1. In combination, a shiftable controlling member, an actuating member therefor, and a floating spring-collapsed toggle acting on 45 said controlling member and collapsible on either side of alined position to tend to move the controlling member toward either of its end positions, said toggle being substantially free from outside lateral pressure and reaction and capable of a limited opening movement from either of its collapsed positions without changing the position of 50 said controlling member.

2. In combination, a shiftable controlling member, an actuating member therefor, a floating spring-collapsed toggle acting on 55 said controlling member and collapsible on either side of alined position to tend to move the controlling member toward either of its end positions, a lost-motion connection between said actuating member and said controlling member, and a connection between 60 an arm of said toggle and said actuating

member for moving that toggle-arm toward alinement with the other toggle-arm as the actuating member moves to take up the lost-motion of its connection with the controlling member. 70

3. The combination set forth in claim 1, with the addition of automatic operating means for said actuating member, said automatic means being affected by variations in conditions controlled by said controlling 75 member.

4. In combination, a shiftable controlling member, an actuating member therefor, a floating spring-collapsed toggle acting on 80 said controlling member and collapsible on either side of alined position to tend to move the controlling member toward either of its end positions, a lost-motion connection between said actuating member and said controlling member, a connection between an 85 arm of said toggle and said actuating member for moving that toggle-arm toward alinement with the other toggle-arm as the actuating member moves to take up the lost-motion of its connection with the controlling 90 member, and automatic operating means for said actuating member, said automatic means being affected by variations in conditions controlled by said controlling member. 95

5. In combination, a shiftable controlling member, an actuating member therefor, a floating spring-collapsed toggle acting on 100 said controlling member and collapsible on either side of alined position to tend to move the controlling member toward either of its end positions, a weight-carrying arm associated with said actuating member and movable through a horizontal position to oppositely inclined positions, and a shifting weight carried by said weight-carrying arm. 105

6. In combination, a shiftable controlling member, an actuating member therefor, a floating spring-collapsed toggle acting on 110 said controlling member and collapsible on either side of alined position to tend to move the controlling member toward either of its end positions, a lost-motion connection between said actuating member and said controlling member, a connection between an arm of said toggle and said actuating member for moving that toggle-arm toward alinement with the other toggle-arm as the actuating member moves to take up the lost-motion of its connection with the controlling 115 member, a weight-carrying arm associated with said actuating member and movable through a horizontal position to oppositely inclined positions, and a shifting weight carried by said weight-carrying arm. 120

7. In combination, a shiftable controlling member, an actuating member therefor, a floating spring-collapsed toggle acting on 125 said controlling member and collapsible on either side of alined position to tend to move the controlling member toward either of its 130

end positions, automatic operating means for said actuating member, said automatic means being affected by variations in conditions controlled by said controlling member, a weight-carrying arm associated with said actuating member and movable through a horizontal position to oppositely inclined positions, and a shifting weight carried by said weight-carrying arm.

10 8. In combination, a shiftable controlling member, an actuating member therefor, a floating spring-collapsed toggle acting on said controlling member and collapsible on either side of alined position to tend to move 75 the controlling member toward either of its end positions, a lost-motion connection between said actuating member and said controlling member, a connection between an arm of said toggle and said actuating member for moving that toggle-arm toward alinement with the other toggle-arm as the actuating member moves to take up the lost-motion of its connection with the controlling member, automatic operating means 80 for said actuating member, said automatic means being affected by variations in conditions controlled by said controlling member, a weight-carrying arm associated with said actuating member and movable through 85 a horizontal position to oppositely inclined positions, and a shifting weight carried by said weight-carrying arm.

9. In combination, a controlling member, an actuating member connected to said controlling member through a lost-motion connection, automatic operating means for said actuating member, said automatic operating means being affected by variations in conditions controlled by said controlling member, 100 means associated with said actuating member and exerting a force thereon tending to move it, said force-exerting means being arranged to produce a variation in said force when the actuating member passes through 105 a predetermined position, and means associated with said controlling member and exerting a force thereon tending to move it, said second force-exerting means being arranged to reverse the direction in which it 110 applies its force on said controlling member as the actuating member acts on said controlling member.

10. In combination, a controlling member, an actuating member connected to said controlling member through a lost-motion connection, automatic operating means for said actuating member, said automatic operating means being affected by variations in conditions controlled by said controlling member, 115 a weight-carrying arm associated with said actuating member and arranged to swing through a horizontal position to oppositely inclined positions as the actuating member moves, a shifting weight carried by said actuating arm and arranged to shift to dif- 120

ferent positions thereon when the arm passes through the horizontal position and thus to vary the mechanical advantage of said weight, and means acting on said controlling member and tending to hold it in either end 70 position it may occupy.

11. In combination, a controlling member, an actuating member connected to said controlling member through a lost-motion connection, automatic operating means for said actuating member, said automatic operating means being affected by variations in conditions controlled by said controlling member, a weight-carrying arm associated with said actuating member and arranged to swing through a horizontal position to oppositely inclined positions as the actuating member moves, a shifting weight carried by said actuating arm and arranged to shift to different positions thereon when the arm passes through the horizontal position and thus to vary the mechanical advantage of said weight, and spring-pressed means acting on said controlling member and tending to hold it in an end position. 90

12. The combination set forth in claim 11, with the addition of means interconnecting said actuating member and said spring-means for varying the effect of the latter as the lost-motion is taken up between said actuating member and said controlling member. 95

13. In combination, a controlling member, an actuating member connected to said controlling member through a lost-motion connection, automatic operating means for said actuating member, said automatic operating means being affected by variations in conditions controlled by said controlling member, means associated with said actuating member and exerting a force thereon tending to move it, said force-exerting means being arranged to produce a variation in said force when the actuating member passes through a predetermined position, means associated with said controlling member and exerting a force thereon tending to move it, and means interconnecting said actuating member and said second force-exerting means for varying the effect of the latter as the lost-motion is taken up between said actuating member and said controlling member. 110

14. In combination, a control valve having a valve stem, an actuating member therefor, operating means for said actuating member, said operating means being affected by variations in conditions controlled by said control valve, a pair of toggle-arms both pivotally connected to said valve stem, said toggle-arms being supported on floating pivots, a spring interconnecting said toggle-arms and tending to move them out of alined position, and means operated by movements of said actuating member for shifting the 125 130

floating pivot of one of said toggle-arms.

15. The combination set forth in claim 14, with the addition of a lost-motion connection between said actuating member and said valve stem.

16. The combination set forth in claim 14, with the addition of a weight-carrying arm which is connected to said actuating member and is arranged to swing through 10 a horizontal position to oppositely inclined positions as the actuating member moves, and a shifting weight carried by said weight-carrying arm and arranged to shift thereon when the weight-carrying arm 15 passes its horizontal position and thus to vary the mechanical advantage of such weight.

17. The combination set forth in claim 14, with the addition of a lost-motion connection between said actuating member and said valve stem a weight-carrying arm 20 which is connected to said actuating member and is arranged to swing through a horizontal position to oppositely inclined positions as the actuating member moves, and

a shifting weight carried by said weight-carrying arm and arranged to shift thereon when the weight-carrying arm passes its horizontal position and thus to vary the mechanical advantage of such weight. 30

18. In combination, a shiftable controlling member having an actuating rod, a pivotally mounted fulcrum sleeve pivotally connected to said actuating rod, a lever arm pivotally mounted in said sleeve, adjusting 35 means for angularly adjusting said lever arm in said sleeve, and a shifting weight carried by said lever arm and shiftable by gravity therealong when the inclination of said lever arm is reversed. 40

19. The combination set forth in claim 18 with the addition of two sets of supports for said fulcrum sleeve on opposite sides of said actuating rod to permit the reversal of the mounting of said sleeve. 45

In witness whereof, I have hereunto set my hand at Indianapolis, Indiana, this 19th day of October, A. D. one thousand nine hundred and twenty three.

ARTHUR E. KRICK.
